UNITED STATES PATENT OFFICE.

JOSEPH G. GRALL, OF DETROIT, MICHIGAN, ASSIGNOR TO ROBERT MITCHELL, OF SAME PLACE.

DESIGN FOR A POLISHING-IRON.

SPECIFICATION forming part of Design No. 33,176, dated September 4, 1900.

Application filed January 31, 1900. Serial No. 3,525. Term of patent 8½ years.

To all whom it may concern:

Be it known that I, JOSEPH G. GRALL, a citizen of the United States of America, residing at Detroit, in the county of Wayne and State of Michigan, have invented and produced a new and original Design for a Polishing-Iron, of which the following is a specification, reference being had therein to the accompanying drawings, in which—

Figure 1 is a side elevation of a polishing-iron embodying my design, in which A represents the boat-shaped body portion sharpened at both ends and provided with a handle B, extending at right angles thereto. Fig. 2 is a plan view of the body portion, and Fig. 3 is a perspective view of the polishing-iron complete.

The leading or material feature of my design consists in the outline and configuration of the boat-shaped body portion A, which in plan has the general shape of an ellipse, point-

ed at both ends, and in side elevation consists in the straight top and bottom parallel thereto for about two-thirds of its length, then gradually curving upward into the substantial vertical ends, the curve of one end being more gradual than that of the other, while in cross-section the configuration is that of a boat with a flat floor, gradually rounding bilges, and straight sides, the sides and top rounding into each other at their meeting edges.

Having thus fully described my invention, what I claim as new, and desire to secure by Letters Patent, is—

The design for a polishing-iron, substantially as herein shown and described.

In testimony whereof I affix my signature in presence of two witnesses.

JOSEPH G. GRALL.
